UNITED STATES PATENT OFFICE.

GEOERGE B. HALL, OF GRAND RAPIDS, MICHIGAN.

DESIGN FOR A RING, PIN, OR ARTICLE OF SIMILAR NATURE.

56,428.

Specification for Design.

Patented Oct. 26, 1920.

Application filed July 16, 1919. Serial No. 311,361. Term of patent 14 years.

To all whom it may concern:

Be it known that I, GEORGE B. HALL, a citizen of the United States, residing at the city of Grand Rapids, in the county of Kent and State of Michigan, have invented a new, original, and ornamental Design for a Ring, Pin, or Article of Similar Nature, of which the following is a specification, reference being had to the accompanying drawing, forming a part thereof.

In the drawing,

Figure 1 is a plan view of the design, its applicability to a ring being illustrated in dotted lines, and

Fig. 2 is a similar view of the design and its applicability to a stick pin.

I claim:

The ornamental design for a ring, pin or article of similar nature, substantially as shown.

In testimony whereof, I affix my signature.
GEORGE B. HALL.
